UNITED STATES PATENT OFFICE.

ANNIE ROONEY McNEAL, OF NEW YORK, N. Y.

TYPEWRITER ATTACHMENT.

Application filed March 29, 1921, Serial No. 456,614. Renewed January 2, 1923.

To all whom it may concern:

Be it known that I, ANNIE R. McNEAL, a citizen of the United States, residing at New York, in the county of New York and State of New York, have invented new and useful Improvements in Typewriter Attachments, of which the following is a specification.

This invention relates to typewriter attachments and comprehends the provision of an article of manufacture which is very simple in construction, so that it can be manufactured and sold at a very nominal cost, and designed to be readily and easily attached to the machine for the purpose of preventing the paper from being blown by drafts or the like in the direction of the operator, thus maintaining the paper in proper position whereby the typewritten matter is always in full view of the operator.

Other objects and advantages of the invention will appear when the following detailed description is read in connection with the accompanying drawing, the invention residing in the combination, construction, and arrangement of parts as claimed.

In the drawing forming part of this application, like numerals of reference indicate similar parts in the several views and wherein:

Figure 1 is a view showing one form of the invention applied to a machine in position for use.

Figure 2 is a view of another form of the invention.

Figure 3 is a sectional view taken on line 3—3 of Figure 2.

Figure 4 is a view of a further modified form of the invention showing the same attached to the paper table of a machine.

Referring to Figure 1 of the drawing, I have illustrated a form of the invention primarily designed for use in conjunction with typewriting machines wherein the carriage is provided with end members A. In this form of the invention I make use of two elements of identical construction and each including a body portion 10 which reposes upon one of the end members A, and provided with a longitudinally disposed slot 11 through which the fastening element 12 is passed for securing the element to the end member. Depending from the outer edge of each element 11 is a flange 13 which contacts the adjacent side of the end member A. Rising from the inner edge of each element

11 is a bifurcated lug 14, these lugs receiving and supporting a rod 15. The rod as shown is arranged in advance of the paper table 16, so as to prevent the paper in the machine from being blown in the direction of the operator, and thus maintaining the paper in a position whereby the typewritten matter is always in view of the operator. By reason of the slot in each of the elements 10, it is manifest that the attachment may be adjusted to properly position the rod 15 with respect to the paper table.

In Figure 2 I have illustrated a modification of the invention, which is designed to be attached directly to the paper table, and used in connection with machines which do not have end members similar to the members indicated at A in Figure 1. In this form of the invention the device embodies two substantially parallel members 17 and 18 respectively, the members 17 being provided with end flanges 19, which support the member 18 in spaced parallel relation from the member 17. It will be noted that the member 17 is arranged at an inclination to the member 18 so as to contact the paper table (not shown) when the attachment is associated therewith. Projecting from the member 17 are attaching ears 20 which are curved to conform to the curvature of the table which they are adapted to engage, each ear being provided with an opening 21 to receive a suitable fastening element to hold the attachment in position upon the machine. It is obvious that the paper when placed in the machine is passed between the members 17 and 18 of the attachment, the member 18 being utilized to prevent the paper from being blown in the direction of the operator.

In Figure 4, I have illustrated another form of the invention wherein 22 indicates a member which is arranged on the underside of the paper table 23 contacting the paper table, and projecting beyond the opposed ends thereof, the member 22 having offset bifurcated extremities 24 which are disposed parallel and in upright positions by twisting the member 22 as at 25. The member 22 is provided with an opening which receives a fastening element 26, and this fastening element may be passed through the paper table if desired, or it may be arranged adjacent the ends thereof, as illustrated in Figure 4, wherein the head of each element is arranged to contact the

table in a manner to hold the attachment in position thereon. The bifurcated extremities 24 of said member receive and support the rod 27 in advance of the paper table, 8 and when the paper is placed in the machine which is passed under this rod 27, the latter serves to prevent the paper from being blown in the direction of the operator.

While it is believed that from the foregoing description the nature and advantages of the invention will be readily apparent, I desire to have it understood that I do not limit myself to what is herein shown and described, and that such changes may be resorted to when desired as fall within the scope of what is claimed.

What I claim is:

1. A typewriter attachment comprising a rod adapted to be arranged in advance of the paper table to prevent the paper from being blown in the direction of the operator, and means secured to the machine and including parallel end members adapted to support the rod in position for use, the said 25 end members being bifurcated to receive and support the ends of the said rod.

2. A typewriter attachment comprising a pair of substantially parallel members, one of which is adapted to be secured to the

paper table of the typewriter, and means 30 carried by the said secured member for engaging and supporting the other member in advance of the paper table, said other member being loosely supported by bifurcated elements of the supporting means. 35

3. A typewriter attachment comprising a rod adapted to be supported in advance of the paper table of the machine to prevent the paper from being blown in the direction of the operator and supporting members attached to the machine and including lugs having bifurcated portions between which the ends of the said rod are adapted to be seated.

4. An attachment for typewriting machines comprising a rod adapted to be arranged in advance of the paper table of the machine to prevent the paper from being blown in the direction of the operator, and support members attached to the machine 50 to receive and support opposite ends of the rod, said rod being disengageable from the said members and the said members being adjustable on the machine for varying the position of the rod with respect to the paper 55 table.

In testimony whereof I affix my signature.
ANNIE ROONEY McNEAL.
